Andrew Little, of New York, N.Y.

Letter Patent 12316-Dated March 1866

Design for Printer's Type

The schedule referred to in my first letter patent and making part of the same
shall be the same as in that letter.

Be it known that I, Andrew Little, of the City, County
and State of New York, have invented or produced a new and original design
for ornamenting printer's type, which I denominate as the "New-Headed
condensed Roman Script"; and I do hereby declare that the following is a full
description of the same.

My invention relates to that class of printer's type known
to the trade as the "Condensed Roman type." To explain the meaning of the
term "condensed," as applied to printer's type, and reducing it to writing
mention is made of the Roman type letters, it will be observed that the
former reduced is not so long as the latter, but that the un-reduced would fit upon
a greater length than width, that is, that it un-reduced would fit upon
a narrow type. It is therefore among printer's type founders much easier in
designing font as if it were another font.

And the nature of my invention consists in shading the "con-
densed Roman type" by means of fine marginal outlines, letter intercypur
rounding all parts of the main letter.

But to describe my invention more particularly, I will refer to the
accompanying drawing, consisting of specimens forming a part of this application,
the same letters of reference having the same referring to like parts.

Figure 1 represents the Alphabet of the "New-Headed-condensed
Roman script."

Des. 2316

2

Letter or is the body of letter, of a heavy black outline, contracted at the sides so as to give the appearance of a long type letter, and thereby produce what is known to the trade as a "condensed Roman letter." Around this narrow body or letter is cut a fine thread or wire outline. This thread or line is equidistant from the edges of the body of the letter, and surrounds it on every side, and may be said to be a skeleton letter with a body letter to print with it.

This peculiarity of shading, it will be observed, differs from my former patent for a semi shaded Roman character in that the former patent described the character as shaded at one side, and that the style of character was Roman type; and therefore was not recognized as the same type.

Having now described my invention of a new design for ornamenting printers type I will proceed to set forth what I claim and desire to secure by Letters Patent of the United States.

What I claim is the design of the semi shaded condensed Roman script type, as hereinbefore set forth.
